CLAIM

The ornamental design for a can carrier, as shown and described.

DESCRIPTION

FIG. 1 is an isometric view of a can carrier showing my new design;

FIG. 2 is a top plan view of FIG. 1, both the top and bottom having the same appearance;

FIG. 3 is a side elevational view of FIG. 1, both sides having the same appearance;

FIG. 4 is an end elevational view of one end of FIG. 1, both ends having the same appearance; and

FIG. 5 is a top plan view of FIG. 1 shown in an unfolded condition.

The broken line showing on FIGS. 1-5 and the can with the indicia on FIG. 1 is for illustrative purposes only and forms no part of the claimed design.
